UNITED STATES PATENT OFFICE.

OLOF PETERSON, OF DE KALB, AND HARRY C. SMITH, OF GENEVA, ILLINOIS.

SAFETY DEVICE FOR ELECTRIC CIRCUITS.

1,116,477.

Specification of Letters Patent. Patented Nov. 10, 1914.

Application filed May 16, 1914. Serial No. 838,929.

To all whom it may concern

Be it known that we, OLOF PETERSON and HARRY C. SMITH, citizens of the United States, residing, respectively, at De Kalb in the county of Dekalb, State of Illinois, and Geneva, in the county of Kane, State of Illinois, have jointly invented certain new and useful Improvements in Safety Devices for Electric Circuits, of which the following is a specification.

Our invention relates in general to safety devices for electric circuits and has for a principal object the provision of a safety device for a circuit carrying a relatively low voltage.

Our invention has particular reference to safety or blow-out devices for use in electric house-lighting circuits where it is extremely desirable to prevent a current of materially higher voltage than that for which the circuit is adapted to be introduced into the circuit. These circuits carry usually a current of 110 or 220 volts which is delivered to them through transformers from a service line or circuit carrying current of much higher potential, often 2200 or 2500 volts. If lightning strikes the service line the insulation in the transformer separating the primary and secondary circuits often breaks down and lets the wires composing these two windings come in contact. When this occurs or when a high tension line wire falls across or comes in contact with a side of a house circuit, the high tension current of the service circuit or other line wire as the case may be is transmitted directly to the house lighting circuit. This usually produces no immediate effect as the devices provided in the house lighting circuit are only concerned with the amperage. Should, however, an individual touch a lighting fixture which is not insulated for such high potential he is likely to form a ground connection and be killed as a result. This high potential in the house circuit often causes, moreover, the breaking down of the insulation of the house circuit and the consequent grounding through pipes or other conductors which results in sufficient sparking to set the house on fire.

It is a principal object of this invention to prevent a current of materially higher voltage than that intended from entering the house circuit or any other circuit in connection with which the device embodying our invention is provided.

A further object of the invention is to provide a safety device of the character described of simple, economical and durable construction which may be easily installed. 60

A preferred form of the invention is to be seen in the drawing accompanying this application of which—

Figure 1 is a plan view, and Fig. 2 is a side elevation partly in section. 65

Referring to the drawing 1 designates a base of suitable insulating material. Upon this base are mounted uprights 2, 2 to which are pivotally connected the knife blades 3, 3 which in turn may engage the clips, 4, 4 70 suitably mounted upon the base. A cross bar 5 and handle 6 of insulating material are provided as is usual in knife-blade switches. Suitably mounted on the base 1 and in electric connection with uprights 2 75 are clips 7, 7 which in connection with similar clips 8, 8 are adapted to hold fuses of standard type. The clips 8, 8 have the usual lugs 9, 9 to which wires may be soldered or otherwise attached. Mounted on the base 1 80 is a coiled spring 10 having an extended arm 11 which passes beneath the insulating cross bar 5 so that when the switch is closed the spring is placed under tension. The spring is made sufficiently strong to throw the 85 knife blades 3 out of contact with the clips 4 when the spring is released. Upon the base 1 is mounted an upright 12 upon which is pivotally mounted a latch 13 which engages the spring arm 11 when the switch 90 is closed and restrains it from displacing the knife blades.

To one of the uprights 2 is attached a wire 14 which is connected with an upright 15 suitably mounted on base 1. To 95 this upright and in electrical connection therewith a fusible wire 16 is attached. The fusible wire 16 is attached at its other extremity to the finger 17 which forms part of the latch 13. The fusible wire 16 passes 100 over a standard 18 which acts as a terminal for a ground wire, the usual lug 21 being provided for connecting the wire. Upon the standard 18 and resting on the surface thereof beneath the fusible wire 16 is a sheet 105 of mica or similar insulating material in the center of which is a small slit or opening 19. The fusible wire is arranged to pass directly over this opening in such a manner that should a high tension current enter the circuit it will develop an arc between the fusible wire 16 and the standard 18, thereby 110

fusing the wire. The wires are connected in the usual manner to the lugs 20, 20 and a ground wire is connected to the lug 21, as previously explained.

5 The operation of our device is as follows: The switch being closed and the spring arm 11 held from acting upon the same by the latch 13, the low tension current will pass through the circuit. Should a 10 high tension current leak into the circuit from any source it will pass through the ground circuit wire 14, upright 15 and fusible wire 16, and overcoming the resistance of the air gap between the fusible wire and 15 the standard 18 it will cause a spark to form which will fuse the wire 16, thereby releasing the latch 13 and the spring arm 11 which will at once open the switch, breaking the circuit and indicating that the abnormal 20 conditions exist in the circuit.

The whole device is simple, efficient and durable and may be readily incorporated in an ordinary circuit, it being necessary only to secure the base 1 to a suitable support and connect the wires in the ordinary manner. A wire should connect the terminal 18 with a suitable ground. The device may be cheaply constructed as its parts 25 may be purchased at any electrical supply 30 house and easily assembled. It will be obvious, moreover, that changes may be made in the form, construction and arrangement of the parts without departing from the spirit and scope of the invention, the device 35 hereinbefore described being merely a preferred embodiment thereof.

We claim:

1. In a safety device for an electric circuit, the combination of a circuit-closing device in said circuit adapted to carry a 40 large volume of current at a relatively low tension, means tending to force said device to open position, means normally restraining said first-mentioned means, and an auxiliary 45 grounded circuit connected to said circuit including spaced conductors adapted to prevent the passage of low tension currents, one of said conductors being fusible and attached at one end to said restraining 50 means.

2. In a safety device for an electric circuit, the combination of a circuit closing device in said circuit adapted to carry a large 55 volume of current at a relatively low ten-

sion, a spring tending to force said device 55 to open position, means normally restraining said spring, and an auxiliary grounded circuit connected to said circuit including spaced conductors adapted to prevent the 60 passage of low tension currents, one of said conductors being fusible at temperatures resulting from electric sparks and attached at one end to said restraining means.

3. In a safety device for an electric circuit, the combination of a circuit closing device in said circuit, means normally tending to force said device to open position, an auxiliary circuit comprising a fusible wire connected at one end with said circuit, and a grounded terminal in close relation to 70 said fusible wire, means for spacing said wire and terminal whereby the passage of low tension currents is prevented, and means connected with the other end of the 75 said fusible wire for restraining the first-mentioned means.

4. In a safety device for an electric circuit, the combination of a circuit-closing device in said circuit, a spring normally tending to force said device to open position, an 80 auxiliary circuit comprising a fusible wire connected at one end with the said circuit, and a grounded terminal in close relation to said fusible wire, means for spacing said 85 wire and terminal, whereby the passage of low tension currents is prevented, and a latch connected with the other end of the said fusible wire for restraining the said spring.

5. In a safety device for an electric circuit, the combination of a circuit-closing device in said circuit adapted to carry a large 90 volume of current at a relatively low tension, a spring tending to force said device to open position, a pivoted latch normally restraining 95 said spring, and an auxiliary grounded circuit connected to said circuit including spaced conductors adapted to prevent the passage of low tension currents, one of said conductors being fusible at temperatures 100 resulting from electric sparks and attached at one end to said latch.

OLOF PETERSON.
HARRY C. SMITH.
